DRIER FOR SHEET MATERIAL

Everett G. Drew, Portland, Oreg.

Application March 19, 1956, Serial No. 572,406

12 Claims. (Cl. 34—43)

This invention relates generally to the drying of a sheet of material as it lies upon and is carried by a heated surface and has air impinged upon it, which air flows over the upper or exposed surface to provide additional drying of said sheet.

This invention is particularly concerned with the formation of a sheet of paper in a paper making machine or drier having a single large drum or cylinder. This type of drier is termed in the art as a "Yankee" type, although it is sometimes known as an "MG" machine. In this type of machine, a continuous, moist paper web is "plastered" against the peripheral surface of a heated drum or cylinder and is held thereto by the surface tension of the moisture lying at the interface of the peripheral surface of the drum or cylinder and the contacted surface of the sheet of paper being formed and dried thereon.

In order to accelerate the drying of the paper, the air which flows over the distant surface of the sheet of paper, that is, the one spaced most distantly from the heated peripheral surface of the drum, is projected by jets directed from perforated or slotted pipes which are spaced some distance from the path of the moving web.

In all such apparatus with which I am familiar, the perforated or slotted conduits have a fixed spacial relationship to the peripheral surface of the drum. This is usually between three to six inches from said surface. Experiments have been performed to vary the velocity of said jets, the temperature thereof, and the angle of incidence of said jets with the opposed surface of the sheet of paper. The greatest difficulty is breaking an overlying stratum of steam or vapor which forms and collects immediately above said sheet and clings to and moves with the upper or outer surface. This sheathes said sheet and blankets the flow of vapor from the sheet as it is produced by the vaporization of the moisture content, by the heated drum upon which said sheet is "plastered."

The spacial relationship has been dictated by the fact that it has generally been assumed that it is necessary to retain a substantial working space or clearance because, frequently, the sheet being formed and dried ruptures, and inasmuch as the sheet is formed and dried with the sheet moving at high lineal velocity, rupturing of the sheet while it passes through the drier causes it to crumple and mass up in said space. This can lodge so tightly in the space that it produces disruptive pressures and scorching of the drum, due to the friction of the massed and crumpled paper as it is restrained by the overlying conduits and rubs against the peripheral surface of the drum. In that event, it is necessary to provide some type of device for prying and pulling said massed and crumpled sheet from said space. A minimal distance of three inches has thus been maintained for this purpose.

Another factor which has limited the proximity of the jets or perforations to the peripheral surface of the drum, the volumes of air impinged and directed over said sheet being dried, and the effective placement of jets, orifices or nozzles is that it is necessary that the air carrying off said vapors must be free to flow quickly

2

away from said sheet and to be exhausted so as to remove moisture from the drier. Efforts have been made to increase the number of nozzles without restricting the discharge of said moisture laden air.

5 I have discovered that I am able to minimize said spacing almost two thirds by arranging jets approximately one inch, and in some instances less, from the peripheral surface of the drum and to direct a multiplicity of small size jets at said optimum spacing, which provides an 10 adequate flow of air over said sheet, and to pinpoint it at closely spaced intervals to make the carry-off of vapors more effective. I do this by providing a multiplicity of conduit sections arranged generally parallel to the axis of rotation of the drum or cylinder and providing each 15 conduit section with a face that is plane. In said plane face which is arranged in opposition to the peripheral surface of the drum, I provide a multiplicity of closely spaced orifices, each carrying a streamlined nozzle through which air or other drying fluid may be directed against the sheet of paper being dried upon said peripheral surface. I arrange a plurality of said conduits in a bank, generally two in number, and each bank is adjustably mounted with respect to the sweep of the peripheral surface of the drum. Said banks may be moved quickly 20 by power means to space said conduits, arranged in bank, from the peripheral surface, so that access may be had in case of breakage and wadding up of a sheet of paper being dried.

I have also discovered that this retraction of the jets 25 from close proximity to the peripheral surface of the drum, and to the sheet carried thereby, may be done automatically by providing sensing devices which produce said retraction immediately following a break or rupture of the sheet, so as to provide a substantially greater working clearance. For example, eight inches of clearance may be had in a matter of seconds. By providing such additional space, the machine may be stopped before damage is done either by production of wedging pressures or by scorching produced by friction of the wad of paper 30 against the peripheral surface of the drum.

Other and important objects of my invention are:

(1) To arrange nozzles in the conduits so that the discharge apertures of said nozzles are in close proximity to the sheet of paper and are in closely spaced pattern, so that the impingement of the air upon the sheet of 45 paper will pierce the overlying stratum of vapor which normally overlies the sheet and flows therewith, and thus break up said stratum and carry it away with the drying air and thus eliminate the blanketing effect of said stratum.

(2) Producing a plurality of closely spaced impact jets directed downwardly upon said sheet of paper with pinpoint effect and in generally uniform pattern which overlies the entire area of the sheet of paper over which air is flowed. This not only aids the drying of a sheet 55 of paper stock, but also produces a hold-down effect to said sheet to augment the so-called "plastering" of said sheet produced by surface tension of the moisture content upon the surface of the drum, or to supplant it if said surface tension is relaxed.

(3) To perform these effects without increasing the number of hot air conduits and without conversely decreasing the area of the passageways necessary to accommodate discharge of vapor laden air from the drier.

(4) To multiply the pressure points developed by the impingement of jets of air upon the surface of the paper several fold by relating the jets to each other to produce intermediate pressure points developed by collision of air from each of said jets upon the other as they are deflected by impact with the surface of the sheet of paper 70 and as they mushroom over the sheet and collide with each other.

(5) To provide nozzles of such small bore that they will produce high velocity directed flow, but which nozzles in total will permit high quantitative flow of air or other drying fluid without increasing the power requirements of the blower system for flowing said air through said conduits and over said sheet.

(6) To provide a patterned flow of air or other drying fluid from said nozzles which discharge close to said sheet, impinge upon it at high velocity, and yet which nozzles are retractable quickly to provide access to the space adjacent said sheet in case of breakage or other emergency.

(7) To provide ready adjustment of said conduits and the nozzles carried thereby, so as to vary the spacing of the discharge outlets of said nozzles with relation to said sheet being dried.

(8) To provide quick acting power means for retracting said nozzles and automatic sensing and operating devices for quickly enlarging the space adjacent the periphery of the drum or cylinder to prevent damage to the drier.

These and other features of my invention, the operation thereof, and the results that flow therefrom are hereinafter described in greater detail with reference to the accompanying drawings, in which:

Fig. 1 is an end elevation of a machine embodying my invention, shown somewhat diagrammatically with respect in the ducts through which drying air flows thereto;

Fig. 2 is a foreshortened elevation of said machine, showing somewhat diagrammatically the ducts for supplying air to the hood and nozzles arranged therein;

Fig. 3 is an enlarged sectional detail view, showing somewhat diagrammatically the nozzles, the jets of drying air emitted therefrom, and the path of flow of said air downwardly toward a sheet of paper, mushrooming therover, and the production of turbulence induced by impact of said mushrooming jets with respect to each other to produce intermediate impingement against a sheet of paper and the production of an increased number of pressure points upon said sheet of paper;

Fig. 4 is a graphic showing of test data, illustrating the relative amplitude of the pressure points and their locations with respect to the jets from the nozzles and the intermediate pressure points developed by collision of the spreading air between the jets to produce turbulence and downward pressure upon the sheet of stock;

Fig. 5 is a plan view of a plane face of a conduit section embodying my invention, showing the pattern of nozzles therein arranged in closely spaced arrangement over the plane surface of said conduit, which surface lies in close proximity to the peripheral surface of the drum or drying cylinder;

Fig. 6 is a somewhat schematic view of the path of the jets of air as they impinge against the sheet of paper, mushroom therover, and impinge against each other to produce the intermediate pressure points between jets, as is illustrated in Fig. 4, said section being taken on the line 6-6 in Fig. 4; and

Fig. 7 is a diagrammatic illustration of the sensing devices, controls and operating mechanism by which said conduits in plural banks may be retracted in case of breakage of the sheet of stock, or otherwise.

My invention is illustrated in connection with a machine which comprises a structural frame 1 mounted upon a foundation 2. Within said frame is a rotatable drum or cylinder 3, over whose peripheral surface 3a a sheet of material 4 is carried and is dried.

Said drum is hollow and is supplied with steam or other heating fluid through a conduit 5 entering the drum substantially at the axis of rotation thereof. A hood 6 overlies approximately 180 degrees of said peripheral surface, as is shown in Fig. 1. Intake conduits 7-7a communicate with the interior of said hood and carry heating air into said hood. Said conduits are provided

with adjustable couplings 8 to accommodate movement of said conduits toward and away from said drum, as will hereinafter be described. The air inflow conduits 7-7a are more or less diagrammatically illustrated in Fig. 2 and supply air to the two sides 6a of said hood.

A multiplicity of longitudinal jetting conduits 10 extend between the two sides of the hood. To facilitate assembly of said jet conduits with the hood sides, I preferably arrange short sections of conduit 6b upon the interfaces of said sides 6a and they terminate in flanges 6c. The jetting conduits are similarly flanged, and the flanges are used to join the jetting conduits between a pair of aligned short sections 6b in the manner illustrated in Fig. 1. It is usual to join these by studs or bolts to facilitate repair and replacement. Air thus flows into said jetting conduits from both ends thereof. This is desirable but not essential, but I have found that this produces sufficient volumes of air for the purpose intended and more uniform jet velocity over the entire portion of the drum and the sheet carried thereby to promote uniform drying of the latter. It is common to heat the air flowing in through the conduits 9-9a under most conditions, and thus a heater is provided (not shown) for heating the air thus applied. Conventional practices may be observed to recirculate air and the efficient utilization of the heat thus supplied to the drying air.

To aid in the retraction of said conduits and the jetting conduits carried thereby, I preferably support and join said conduits in two or more banks, as is illustrated in Fig. 2; that is, one bank lies to one side of the centerline of said figure and the other bank lies at the opposite side thereof. Each bank of conduits is provided with parallel guides 11-11a which are fixed to the structural frame 1. Rollers 12-12a engage the guides 11-11a, respectively, and each of said rollers is carried by its bank of conduits at each end thereof. That is to say, one set of guides 11-11a lies at the end of a bank facing the viewer in Fig. 2, and a companion set is arranged at the opposite end. A beam 13 extends intermediate the ways of guide 11 and spans the entire length of the conduits to give structural strength and rigidity thereto. Pairs of power cylinders 14-14a aligned with the guides 11 have their pistons 15-15a joined to said beam at its opposite ends by means of piston rods 16-16a and connecting links 17-17a. The connecting links join the cylinder through pad eyes 18.

In order that both banks of conduits will be retracted uniformly and the ends of each bank will be lifted equally, I join the pistons 15-15a by a shaft 19 which is rotated by connection with the pistons 17-17a, as is illustrated in Fig. 1. Intermediate the connection of said shaft with the cylinders, I arrange a pair of arms 20, links 21 and pad eyes 22. Thus, as the shaft 19 turns back and forth, it will swing the pairs of arms secured thereto equal radial swings and will pick up and return each of the conduit banks equally and uniformly.

Said banks of conduits carry the jetting conduits, as has been described, and thus when the banks of conduits are arranged as illustrated in Fig. 1, it is necessary that the conduits occupy a correct spacial relationship with regard to the peripheral surface 3a of the rotatable drum. This is accomplished by providing an adjusting screw 23, carried by a bracket 24, and joined in turn with the structural frame 1. Each of said adjusting screws is threaded in its bracket, and thus by turning it, it will extend further from or closer to the face of the bracket. The end of each adjusting screw engages the under surface of the beam 13 at each end thereof, and the screw may be locked in adjusted position by a lock nut 23a. There are two adjusting screws for each bank of conduits; that is, there are four adjusting screws, two of which engage the beam on the left hand bank of conduits, one at each end, and a similar arrangement is provided for the right hand bank of conduits.

As viewed in Fig. 1, the drum or cylinder 3 rotates in a counterclockwise direction, as is indicated by arrows. The sheet of material 4 overlies the peripheral surface 3a thereof, and thus the paper enters at the lower right hand side of said figure and is discharged at the lower left hand side. Supported by the guide 11a at said right hand side which forms a part of the fixed framework of the machine is a feeler or sensing device 25. It has a riding arm 25a which rests lightly upon the sheet of material and which is carried along by the drum. If said sheet of material breaks, the feeler or sensing device is tripped to cause the power cylinders to lift the jetting conduits more or less radially from the drum a distance of about eight inches, so as to provide a large working clearance between the peripheral surface of the drum and the most closely adjacent surfaces of the jetting conduits 10. I have illustrated this somewhat diagrammatically in Fig. 7.

It is to be understood that the feeler or sensing device 25 and its riding arm 25a is only exemplary of any type of sensing device. The ultimate end which I have in mind is to provide a device which will sense a break or rupture in the sheet of material 4. This may be mechanical-electrical, as is illustrated and described, or it might be photoelectric in which the presence of the uninterrupted sheet of material intercepts the beam, and when said sheet is broken, the maintenance of the beam will actuate the means for moving the jetting conduits 10 and their nozzles away from the peripheral surface of the drum in order to provide the desired clearance. The feeler or sensing device also might bear upon a span of paper as it is discharged from the roller rather than to sense it at the point of entry of the moist stock under the hood. The advantage of the location selected and illustrated, however, is that it is at this point that any massing or crumpling of paper would be initiated, in all probabilities, and as the paper, following a break, would tend to mass up at this point and would produce pressure which would be sensed by and transmitted to the operating mechanism, which would respond to the emergency condition thus created and the parts would be rapidly separated before damage occurred.

As is shown in Fig. 7, the feeler or sensing device actuates a switch 26 in the control circuit 27. The actuation of said switch operates a hydraulic valve 28 by means of a solenoid 29 to supply fluid through the conduit system 30 to all four power cylinders 14-14a. The actuation of said cylinders causes the bank of conduits to be quickly lifted, that is, retracted from the drum, as has been described. Said jetting conduits are quite massive and will return by gravity to the position they occupy in Fig. 1 when the sensing device 25 is returned into bearing relationship with the sheet of material. I preferably provide a main control switch 31 in the electrical control circuit 27. Said main control switch or other control element can make the operation and retraction of said parts manual rather than automatic and also provide a safety factor for holding the parts spaced apart, if such is desirable.

Referring now to Figs. 3 and 4:

It is desirable that the face wall 32 of each of the conduits 10 follow generally the sweep of the peripheral surface 3a of the rotatable drum. Thus, said conduits 10 are arranged generally in a circular course surrounding and facing said peripheral surface, as is shown in Fig. 1. Said conduits preferably are of rectangular section, as is shown in said figure, and in a typical installation said conduits are approximately twelve inches deep. They extend the full width of the paper, as is indicated in Fig. 2.

Machines generally accommodate sheets of paper stock from about eight feet wide to about twenty feet wide, and thus each of the conduits 10 is of corresponding length. I have found that I get the best results by providing nozzles 33, each having a discharge aperture of about one-

quarter inch, the nozzles being three-quarters inch long. They preferably are of the reentrant type, that is, they lie inwardly of the face wall 32 and terminate the exterior face of wall 32. I have found that nozzles of streamlined contour operate most efficiently. In all drying machines with which I am familiar, in which air is directed by jets over a surface of a sheet to be dried, the apertures or discharge nozzles have either been perforations through the wall of the conduit, or standrad mouth pieces, or else they have been reentrant tube discharge outlets or examples of Borda's mouthpiece. A Borda mouthpiece is one in which the reentrant tube is of cylindrical form and is half as long as the diameter of the orifice. The reentrant tubes have extended inwardly from the face fo the conduit a distance two or three times the diameter of the orifice. With a Borda mouthpiece, high velocities are attainable on the order of an empirical scale of about 99, but the quantitative flow is on the order of 54 on a similar scale. The reason is that the Borda mouthpiece contracts the jet as it flows over the relatively sharp entrance edge, which substantially restricts the volume to produce the higher velocity. On the other hand, a reentrant tube two or three times as long as the diameter of the orifice cuts down the velocity to about 72 on said scale and has a quantitave flow of about 72.

I have discovered by measurement and test that with a bell-shaped reentrant tube of streamlined contour such as is illustrated in Fig. 3, the velocity is maintained at about 96 on said scale and the quantitative flow is about 96. Thus, jets of high velocity are emitted and there is little restriction to flow through the orifice. The emitted jet also seems to hold its cylindrical pattern or cross section better than one emitted by either of the other two orifices. That is to say, the angle of divergence seems slight, and thus the entire jet of air is directed throughout its cross section upon or to the surface, or adjacent the stratum of overlying air or vapor, before it tends to spread out and mushroom and sweep over the surface of said paper. This is graphically shown in Fig. 4.

The peaks x underlie the axis of the jet emitted from each nozzle and they descend quite sharply. Lying intermediate said peaks are ones of lower amplitude y which develop when nozzles one-quarter inch in discharge aperture size, three-quarters inch long, belled as is shown, and spaced apart one and a quarter inches apart are arranged approximately one inch away from the upper surface of a sheet of paper to be dried. I am unable to explain definitely why these intermediate peaks occur, but they do. It seems logical to suppose, as is illustrated diagrammatically in Fig. 3, that they are produced by the impinging of adjacent mushrooming jets as the jets flow over the surface of the sheet of paper. They likewise rise and fall sharply. In said test, air velocities were maintained slightly above 13,000 feet per minute. When the spacing is increased above one inch, said intermediate peaks rapidly diminish and flatten out, and this is likewise true when a spacing of the nozzle to the paper is less than one-half inch. The amplitude of the major peaks x increases substantially at the smaller spacing, but the intermediate peaks do not occur. This is critical between an orifice spacing from the sheet of from one-half inch to two inches and with jets having outlet diameters of from three-sixteenths inch to one-half inch at the attained velocities. I believe this to be an important factor in the efficient drying of paper because the production of these numerous pressure points or applications of impact air to the sheet produces more rapid drying of said sheet. My experience, further, has been that when an optimum relationship such as described is maintained, there is a substantially less tendency to rupture the sheet of paper being dried than previously. Certainly, the pressure generated by said numerous impact points would tend to hold the sheet to the surface of the drum more securely than if they were not of the attained amplitude and

pattern. Normally, the paper is "plastered" to the peripheral surface of the drum by the surface tension of the water content of the sheet where it lies as a film between the opposed surfaces of the sheet and the drum. If the sheet dries too rapidly at the interface and said water film is vaporized unevenly, the uniform surface tension is relaxed and the paper tends to "blow off" the peripheral surface of the drum.

The presence of the plurality of pressure points, say three-fourths inch apart over the entire area, would tend to provide some force greater than a generally elevated air pressure extending over the sheet, to prevent dislodgment of the sheet from the peripheral surface of the drum. In any event, in my experience, the rupturing of the sheet and the consequent stopping of the machine has been materially diminished when my invention has been used, and my observation of the factors involved leads me to the conclusion that this is produced by the uniform pattern of closely spaced pressure points over the entire sheet of paper being dried under the air hood.

In Fig. 6, I have shown somewhat schematically the flow lines produced when a jet strikes the surface of the paper, which is arranged substantially normal to the jet, as is illustrated. The outward flow or splatter over the sheet of paper quickly strikes the opposed outward flow from adjacent jets and the splatter produced by collision with adjacent jets. The impact of two of said jets moving in opposite directions and of approximately equal velocities would produce a downward flow, or at least a downward component of force, against the surface of the paper. This is evidenced by graphs developed by numerous tests. In other words, said midpoints x and y shown on the graph in Fig. 4 do occur routinely, and it is for the reason, I believe, that I have just described.

Said peaks are developed by impact of the jets upon a surface of the sheet of stock being dried. They are of relatively high amplitude and tend to pierce the stratum of vapor which is possibly a thousandths or two-thousandths of an inch in thickness. Said stratum is developed by the heat of the drum in the paper stock, and tends to blanket the stock and to inhibit the outward flow of following vaporous moisture from the stock. By piercing this blanket in numerous places and sweeping it in a turbulent flow from proximity with a sheet of stock, I eliminate said blanketing influence and accelerate the rate at which vapor is absorbed by the air and carried out of the drier and, correspondingly, increase the rate at which the stock is dried. As has been pointed out, the sum of the number of peaks x and y is double that of the nozzles in each row and is augmented between successive rows. Thus, with the same number of nozzles or orifices, the pressure points are patterned more closely and are increased substantially in number without the addition of other nozzles, which was heretofore considered necessary.

The provision of bell-shaped reentrant tubes, or so-called streamlined contour nozzles, permits the orifices of the several nozzles to be diminished in diameter and the number of nozzles to be increased without correspondingly decreasing the volume of flow of air through said nozzles. This permits me to use nozzles of from three-sixteenths inch to approximately one-half inch diameter rather than from five-eighths inch to one inch in diameter, as was previously done. I believe this to be a matter of consequence because resistance to flow through an aperture is substantially inversely in proportion to the square of area of the aperture. Thus, when apertures one-half inch in diameter are used rather than those of one inch in diameter, the area of said apertures is diminished three quarters. When air is forced through an aperture one-quarter inch in diameter, it has a cross sectional area of only one-sixteenth that of an inch diameter aperture. The volume of air which necessarily must be flowed through driers of this type and capacity require blowers of large size to be

utilized, and the power requirements for said blowers range from 250 H.P. to 500 H.P. It is thus essential that the air flow through said apertures at high velocity and minimum restriction, particularly as far as volumetric flow is concerned. Said bell-shaped reentrant tubes or streamlined orifices perform this function well and produce jets having the desirable characteristics to which I have hereinabove referred.

I have not illustrated the encompassing hood or room into which the discharged moisture laden air flows from the hood because this is more or less conventional and is well known in the art. In any event, this air is sometimes wholly wasted to the atmosphere, sometimes wholly recirculated, and at other times it is intermixed with proportionate make-up air and returned to the machine through the intake ducts 6-6a. The recirculation or wasting of the generated heat depends upon circumstances and specific installations and forms no part of my invention.

20 I claim:

1. A paper-making machine for drying a continuous sheet of material directed over the peripheral surface of a rotatable drum which is maintained at a temperature substantially above atmospheric, comprising a hollow hood member partially encircling the periphery of said drum, means for directing air under pressure to the interior of said hood, a series of longitudinally disposed conduits arranged in a circular sweep generally concentric with the peripheral surface of said drum, and streamlined-bore bell-shaped nozzles arranged in each of said conduits and having discharge outlets directed toward the peripheral surface of said drum, where the nozzle diameter is less than approximately one-half inch, the nozzles are spaced less than approximately two and one-half inches apart, and said nozzles terminate less than approximately two inches from the drum surface.

2. A paper-making machine for drying a continuous sheet of material directed over the peripheral surface of a rotatable drum which is maintained at a temperature substantially above atmospheric, comprising a hollow hood member partially encircling the periphery of said drum, means for directing air under pressure to the interior of said hood, a series of longitudinally disposed conduits each having a wall arranged in a circular sweep generally concentric with the peripheral surface of said drum, and reentrant-type streamlined-bore bell-shaped nozzles arranged in each of said conduits and having discharge outlets terminating at the exterior face of said wall and directed toward the peripheral surface of said drum, where the nozzle diameter is less than approximately one-half inch, the nozzles are spaced less than approximately two and one-half inches apart, and said nozzles terminate less than approximately two inches from the drum surface.

3. A paper-making machine for drying a continuous sheet of material directed over the peripheral surface of a rotatable drum which is maintained at a temperature substantially above atmospheric, comprising a hollow hood member partially encircling the periphery of said drum, means for directing air under pressure to the interior of said hood, a series of longitudinally disposed conduits each having a wall arranged in a circular sweep generally concentric with the peripheral surface of said drum, each of said conduits having a generally plane exterior face carrying a plurality of equidistant rows of nozzles including a plurality of nozzles spaced a predetermined distance apart in each row and terminating at the exterior face of said wall, where the nozzles are less than one inch in diameter, are spaced apart in each row less than approximately two inches and terminate less than approximately two inches from the drum surface.

4. Claim 3 modified in that said nozzles are less than one-half inch in diameter and are spaced apart from adjacent nozzles a distance less than two inches, and more than one-half inch.

5. Claim 3 modified in that said nozzles are less than one-half inch in diameter and are spaced apart from adjacent nozzles a distance less than two inches, and that the discharge outlets of said nozzles are spaced from the peripheral surface of said drum a distance less than two inches, and more than one-half inch.

6. Claim 3 modified in that said nozzles have discharge outlets approximately one-quarter inch in diameter, are spaced approximately one and one-quarter inches from adjacent nozzles over the generally plane face of each conduit, and are spaced from the peripheral surface of said drum approximately one inch.

7. Claim 3 modified in that said nozzles have the following proportionate relationship with respect to each other, the discharge outlets are approximately one-quarter inch in diameter, are spaced approximately one and one-quarter inches from adjacent nozzles over the generally plane face of each conduit, and are spaced from the peripheral surface of said drum approximately one inch in the range of one-half inch to two inches.

8. A paper-making machine for drying a continuous web of material directed over the peripheral surface of a rotatable drum which is maintained at a temperature substantially above atmospheric, comprising a hollow hood member above and partially encircling the periphery of said drum, said hood comprising plural sections mounted for movement along diverging substantially radial separate paths, means for directing air under pressure to the interior of said hood, a series of longitudinally disposed conduits arranged in a circular sweep generally concentric with the peripheral surface of said drum, nozzles arranged in each of said conduits and having discharge outlets directed toward the peripheral surface of said drum, sensing means responsive to web breakage and operating means activated by said sensing means upon web breakage to lift said nozzles from the peripheral surface of said drum as units to provide access to a space of substantially uniform breadth between the conduits and the peripheral surface of said drum.

9. Claim 8 modified in that said pressure-sensitive operating means are power actuated.

10. A paper making machine for drying a continuous web of paper directed over the peripheral surface of a rotatable drum, which drum is maintained at a temperature substantially above atmospheric, comprising a hollow hood member comprising plural units, each unit occupying about 90° of the circumference of said drum, individual means for directing air under pressure to each of said hood units, a conduit carried by each of said hood units into which said means discharges, each conduit having a wall arranged upon a circular sweep generally concentric with and adjacent the peripheral surface of said drum, plural guideways for each of said units defining a path of travel toward and from said drum, which path is substantially radial to the circular sweep of the unit being guided, said pathways thereby diverging with respect to each other, sensing means responsive to web breakage, and means activated by said sensing means upon web breakage for moving said plural units simultaneously toward and from said rotatable drum, each along its respective path.

11. A paper making machine for drying a continuous

5 web of paper directed over the peripheral surface of a rotatable drum, which drum is maintained at a temperature substantially above atmospheric, comprising a hollow hood member comprising plural units, each unit occupying about 90° of the circumference of said drum, individual means for directing air under pressure to each of said hood units, a conduit carried by each of said hood units into which said means discharges, each conduit having a wall arranged upon a circular sweep generally concentric with and adjacent the peripheral surface of said drum, plural guideways for each of said units defining a path of travel toward and from said drum, which path is substantially radial to the circular sweep of the unit being guided, said pathways thereby diverging with respect to each other, sensing means responsive to web breakage, means activated by said sensing means upon web breakage for moving said plural units simultaneously toward and from said rotatable drum, each along its respective path, said means moving each of said head units over a predetermined range of movement along its path between preselected limits.

12. A paper making machine for drying a continuous web of paper directed over the peripheral surface of a rotatable drum, which drum is maintained at a temperature substantially above atmospheric, comprising a hollow hood member comprising plural units, each unit occupying about 90° of the circumference of said drum, individual means for directing air under pressure to each of said hood units, a conduit carried by each of said hood units into which said means discharges, each conduit having a wall arranged upon a circular sweep generally concentric with and adjacent the peripheral surface of said drum, plural guideways for each of said units defining a path of travel toward and from said drum, which path is substantially radial to the circular sweep of the unit being guided, said pathways thereby diverging with respect to each other, sensing means responsive to web breakage, and means activated by said sensing means upon web breakage for moving said plural units simultaneously toward and from said rotatable drum, each along its respective path, each conduit wall of a hood unit having nozzles terminating in a common sweep at the surface of said wall adjacent said drum, the means moving said head units a substantially uniform distance along said path, thereby to provide access to a space of substantially uniform breadth between all of the conduit walls and the peripheral surface of said drum.
